(57) **CLAIM**

The ornamental design for a poop scooper, as shown and described.

DESCRIPTION

FIG. 1 is a perspective view of a poop scooper, showing a switch door being closed;

FIG. 2 is the left view thereof;

FIG. 3 is the right view thereof;

FIG. 4 is the front view thereof;

FIG. 5 is the rear view thereof;

FIG. 6 is the top view thereof;

FIG. 7 is the bottom view thereof; and,

FIG. 8 is a perspective view of a poop scooper, showing the switch door being open.

The broken lines illustrate portions of the article that form no part of the claimed design.
